(21) Appl. No.: **29/197,306**

CLAIM

(22) Filed: **Jan. 14, 2004**

The ornamental design for an ergonomic luggage handle, as shown and described.

(51) LOC (8) Cl. **03-01**

DESCRIPTION

(52) U.S. Cl. **D3/318**

FIG. 1 is a perspective view of the front of an ergonomic luggage handle of the invention, showing our new design in the context of a piece of luggage with the handle in the down position.

(58) Field of Search D3/279, 282, 318,

FIG. 2 is a front view of the ergonomic luggage handle of the invention.

D3/328, 324; D8/302, 306, 316, 317, 319,

FIG. 3 is a side view of the ergonomic luggage handle of the invention.

320; D34/24, 26; 190/18 A, 39, 102, 103,

FIG. 4 is a top view of the ergonomic luggage handle of the invention.

111, 115; 280/37, 47.26, 655, 655.1; 16/110.1,

FIG. 5 is a bottom view of the ergonomic luggage handle of the invention.

113.1, 114.1, 405, 406, 408, 445, 421,

FIG. 6 is a perspective view of the front of an ergonomic luggage handle of the invention, showing our new design in the context of a piece of luggage with the handle in the up position, parallel to the ground.

422, 429, 430, 431

FIG. 7 is a perspective view of the front of an ergonomic luggage handle of the invention, showing our new design in the context of a piece of luggage with the handle in the fully up position, perpendicular to the ground; and,

(56) **References Cited**

FIG. 8 is a perspective view of the front of an ergonomic luggage handle of the invention, showing our new design in the context of a piece of luggage with the handle in the down position and stored within the luggage.

U.S. PATENT DOCUMENTS

The broken line showing of a suitcase and towing member in FIGS. 1-3, and 6-8, is for illustrative purposes only and forms no part of the claimed design.
